United States Patent Office

Des. 202,438

Patented Sept. 28, 1965

202,438

FLOOR LAMP

Morris Lange, Shaker Heights, Ohio, assignor to Superior Funeral Supply Corporation, Cleveland, Ohio, a corporation of Ohio

Filed Dec. 8, 1964, Ser. No. 82,952

Term of patent 14 years

(Cl. D48—20)

Fig. 2

I claim:

The ornamental design for a floor lamp, as shown and described.
